UNITED STATES PATENT OFFICE

2,469,302

TRANSITORY GARMENT

Lynden M. Kelleher, San Francisco, Calif.

Application December 12, 1945, Serial No. 634,499

4 Claims. (Cl. 2—69)

1

The instant invention relates to transitory garments, and more particularly to bath towels adapted to be worn on occasion as partial body garments.

In numerous instances it is well for the inherent modesty of man that he be afforded a temporary, secure, and not unwieldy instrumentality for bodily coverage, i. e., in transit during physical examination, as prior to or during military service; or during passage between locker-room and shower facilities in recreational centers, to enumerate but a few of said instances.

On these occasions, man has decided that it is not quite feasible to utilize the dressing gown or bath-robe, not only because such items are cumbersome and generally not handily available, but also because man, being on the average a respecter of mass opinion, feels that such efforts will be frowned upon as picayunish.

Accordingly, it is conventional for man to attempt to partially clothe himself in a towel held to his person by some insecure contrivance or by a clutching action of the hands. The latter method restricts the wearer to a freedom of action of one hand only, while the former method, at best, is troublesome by its very insecurity, filling the wearer with anticipatory qualms.

As a helpful aid in the above described situations, I have invented novel and useful means for securing a bath towel to the body of a person to serve as a transitory garment.

An object of my invention is to provide a bath towel having means embodied therein to secure said towel in skirt-fashion to the person of a wearer.

Another object of my invention is to provide a bath towel having variable fastening means to adapt said towel to comfortably encompass a portion of the body of persons of widely variable girth.

Other objects and advantages of my invention will be readily apparent from the following description taken in conjunction with the drawing forming part of this specification, and in which:

Fig. 1 is a view in elevation of the towel and securing means embodied in the invention;

Fig. 2 is a partial plan view of one of the securing means embodied in the invention; and

Fig. 3 is a partial plan view of the other of the securing means embodied in the invention.

Referring to the drawing for more specific details of the invention, 10 is a conventional rectangular bath towel having a pair of parallel edges 12 and a pair of parallel edges 14.

A ribbon 16 having one end adjacent a corner

2

of the towel and being arranged parallel to an edge 12 and in close proximity thereto is secured to the towel by a plurality of spaced rows of threads 18 transverse of the ribbon providing a plurality of loops 20.

In the opposite corner of the towel near the same edge 12, a short length of ribbon 22 is secured by threads 24, and at the free end of the ribbon there is secured, as by sewing, a braided 10 knot or cloth button 26.

The towel is adapted to be affixed to the wearer as a pseudo-skirt for purposes above described by encircling the towel about the body with the edges 14 substantially normal to the ground and 15 inserting the button 26 through one of the loops 20 appropriate to the circumferential proportions of the wearer.

When the towel is on the wearer, the button 26 is normally inhibited from passing through the 20 loop 20 to unbind the garment by the tautness of the ribbon resulting from a slight outward pressure exerted on the towel by the wearer and the weight of the towel supported by the ribbon.

The cloth fastening means allows for repeated 25 launderings of the towel with no deleterious effects to said means. Fastening means of a material other than cloth are generally vulnerable to loss of elasticity, breakage or loss of solid buttons upon stringent repeated laundering.

30 The absence of metal material in the fastening means prevents the possibility of high heat conducting means coming into contact with the wearer's body and causing discomfort to the wearer.

What I claim as new and desire to secure by 35 Letters Patent is:

1. Fastening means for a skirt-like garment adapted to be worn with the upper edge thereof encircling the waist of the wearer and with the end edges thereof in overlapped relation, said 40 means comprising an elongated strip of fabric gathered into a plurality of substantially semi-circular loops along its length and having the portions thereof between the loops secured to the garment, said strip being located adjacent the 45 upper edge of the garment and one of its end edges and being substantially parallel to said upper edge of the garment, and another elongated strip of fabric having an end portion thereof secured to the garment adjacent the upper edge 50 and the other end edge of said garment and having a free end with a button thereon, the secured end portion of said other strip being substantially parallel with said first-mentioned strip and being located in closer relation thereto than the free 55 end of said other strip, said loops being of such

size in relation to said button that the latter is adapted for full-bodied introduction through a selected loop to secure the garment around the waist of a wearer whereupon the weight of the hanging garment as applied to the selected loop distorts said loop sufficiently to prevent accidental disengagement of said button therefrom.

2. Fastening means for a skirt-like garment as set forth in claim 1 wherein the distance between said button and the loop of said first-mentioned strip farthest removed therefrom as measured along the upper edge of the garment is sufficiently greater than the distance between said button and the loop of said strip closest thereto so that the difference between said two measured distances substantially coincides with the difference between the maximum average and the minimum average waist measurements of wearers of skirt-like garments.

3. A skirt-like garment having an upper edge and oppositely disposed end edges and adapted to be worn with the upper edge thereof encircling the waist of the wearer and with the end edges thereof in overlapped relation, an elongated ribbon-like strip of fabric gathered into a plurality of substantially semi-circular loops along its length and having the portions thereof between the loops secured to the garment, said strip being located on one surface of the garment adjacent the upper edge and one of the end edges of the garment and being substantially parallel to said upper edge, and another elongated strip of fabric having an end portion secured to that surface of the garment to which said first-mentioned strip is attached and adjacent the upper edge and the other end edge of said garment, said other strip having a free end provided with a button and having its secured end portion in substantial parallelism with said first-mentioned strip and located in closer relation thereto than said free

end, said loops being of such size in relation to said button that the latter is adapted for full-bodied introduction through a selected loop to secure the garment around the waist of a wearer, 5 whereupon the weight of the hanging garment as applied to the selected loop distorts said loop sufficiently to prevent accidental disengagement of said button therefrom.

4. A skirt-like garment as set forth in claim 3 10 wherein the distance between said button and the loop of said first-mentioned strip farthest removed therefrom as measured along the upper edge of the garment is sufficiently greater than the distance between said button and the loop of 15 said strip closest thereto so that the difference between said two measured distances substantially coincides with the difference between the maximum average and minimum average waist measurements of wearers of skirt-like garments.
